CARL J. LANDIN, OF BOSTON, MASSACHUSETTS, ASSIGNOR TO CLIFTON MANUFACTURING COMPANY, OF BOSTON, MASSACHUSETTS, A CORPORATION OF NEW JERSEY.

MACHINE FOR FEEDING FABRICS AND THE LIKE.

1,110,633.

Specification of Letters Patent. Patented Sept. 15, 1914.

Application filed October 17, 1910. Serial No. 587,399.

To all whom it may concern:

Be it known that I, CARL J. LANDIN, a citizen of the United States, and a resident of Boston, in the county of Suffolk and State of Massachusetts, have invented an Improvement in Machines for Feeding Fabrics and the like, of which the following description, in connection with the accompanying drawings, is a specification, like letters on the drawings representing like parts.

This invention relates to the feeding of fabrics or other materials in coating or other machines.

The character of the invention may be best understood by reference to the following description of an illustrative embodiment thereof shown in the accompanying drawings, wherein:

Figure 1 is an interrupted, vertical, longitudinal section through a coating machine illustrated herein as embodying my invention; Fig. 2 on an enlarged scale illustrates a roll shown in Fig. 1 and connections for starting the fabric into the machine; Fig. 3 on an enlarged scale illustrates a take-up roll shown in Fig. 1; Fig. 4 is a plan of Fig. 3; Fig. 5 on an enlarged scale illustrates the construction of an end of an apron used in the machine; Fig. 6 is a side elevation of Fig. 5; Fig. 7 on an enlarged scale illustrates a hook plate shown in Fig. 2 for detachably connecting the fabric to the apron; Fig. 8 is a side elevation of Fig. 7; Fig. 9 is a view similar to Fig. 7 showing the apron and fabric connected to the hook; Fig. 10 is a side elevation of Fig. 9; Figs. 11 to 16 are diagrammatic views illustrating steps in the process of introducing the fabric to the machine; and Figs. 17 and 18 are details to be referred to.

Referring to the drawings, the illustrative apparatus shown herein as embodying my invention comprises a let-off roll 11 (Fig. 1) on which the fabric to be treated may be previously wound. To introduce this roll into the machine it may be slipped on to a rectangular shaft 13 having rounded ends for insertion in open bearings 15 on brackets 17 projecting laterally from the feeding-in end of the machine frame 19. The fabric or material on the let-off roll may be led diagonally upward to and over a rubber coated or equivalent roll 21 journaled in bearings in the machine frame and driven

by any suitable mechanism, not shown. Said fabric passes beneath a scraper coating knife 23 located above said roll and having trunnions 25 journaled in boxes 27 adapted to be vertically adjusted in guides 29 by screws 31 and hand wheels 33.

The fabric led between the roll 21 and knife 23 may receive a coating of rubber composition or other material. This material is usually viscous and may be laid on a portion of the fabric on the roll 21 back of the knife 23. As the fabric is fed between said knife and roll the rubber composition will crowd against the knife and be spread or distributed thereby in the form of a thin coating on the fabric.

In order to dry the fabric thus coated the fabric is led a considerable distance from the coating roller 21 to and over a guide roller 35 (Fig. 1) preferably larger in diameter than the roller 21 and mounted on a shaft 37 journaled in suitable bearings on the machine frame. The guide roller may be driven from the shaft of the coating roll by any suitable gear connections (not shown) including a suitable clutch for controlling the starting and stopping of the guide roller. The drying of the coating may be assisted by heat radiators, not shown, if desired.

The fabric is led from the guide roller 35 downwardly and thence diagonally forwardly toward the feeding-in end of the machine and to a take-up roll 39. To permit this roller to be readily introduced into or taken from the machine for purposes hereinafter described said roller may be slid on a square shaft 41 having rounded ends for insertion in open bearings 43 in brackets 45 projecting laterally from the machine frame. This take-up roll may be driven in any suitable manner by means not shown herein.

Heretofore, so far as I am aware, the introduction of the fabric into the machine has been by a slow and crude process. This has been effected by sewing a long, introductory strip of cheap material to the end of the fabric. The end of said strip is then led manually upwardly over the rubber coated roll 21, beneath the coating knife 23 thence rearwardly to and over the guide roller 35 at the remote end of the machine; then under said roller back toward the feeding-in end of the machine where it is se-

cured to the take-up roll 39. Not only does the leading in of the fabric in this manner require a great deal of time, but also it is impossible to sew the leading strip to the 5 fabric to be treated without causing a series of wrinkles in the fabric adjacent the seam forming the juncture thereof with said strip when said strip is tensioned as in feeding. In order that the thin coating may be 10 properly applied it is necessary that the fabric should be absolutely smooth. This wrinkling prevents a proper application of the coating material for several feet adjacent the seam and as a result this portion of 15 the fabric is wasted. Furthermore, it is necessary to watch the leading in strip at the guide roller 35 and manually smooth out the wrinkles which are bound to occur at this point in order that the following fabric 20 may be smoothly guided over said roller. A similar strip, also, must be sewed at the trailing or last end of the fabric to pass through the machine in order that the end of the fabric may not trail loosely through 25 the machine after leaving the roll 21. Here again at the juncture of the trailing strip with the fabric occurs the objectionable wrinkling of the fabric with consequent waste of a portion of the fabric at said 30 seam due, as stated, to the inability to properly coat a wrinkled fabric.

By my invention the above and other objections to the above described crude method of feeding the fabric through the machine 35 are overcome. By my invention it is unnecessary to sew long, introductory and trailing strips or aprons at the ends of the fabric to be treated but, instead thereof, I use means which I will now describe. As shown here- 40 in this means comprises an apron or strip 47 of canvas or other strong material of sufficient length to extend from the coating roll 21 or feeding-in end of the machine rearwardly to the guide roller 35 and thence 45 to the take-up roller 39.

To stiffen or spread the end edges of the apron, tips or strips 49 (Figs. 5 and 6) of metal may be permanently secured thereto. This may conveniently be effected by placing an end portion of the apron on an elongated sheet of metal or other suitable material. The superposed parts may be then folded in plural ply form thereby securely retaining the tips on the ends of the 55 apron.

To connect an end of the apron to the take-up roll, eyes 51 (Figs. 4 and 5) may be formed in the apron adjacent the inner edges of the tip on such ends, said eyes being 60 adapted to receive screws 53 or equivalent projections spaced on said take-up roll at points corresponding to the positions of the eyes 51. When the eyes are placed on said screws and the roll is rotated, the screws 65 will engage the inner edge of the apron tip

49 and the apron will be drawn by a pull evenly distributed along the tip without wrinkling. This connection is superior to the mode of attachment hitherto used wherein the apron end was without any 70 spreader tip and the connection of the apron to the roll was had merely by passing the apron end once around the roll and tucking the same in under the standing part of the apron, thereby forming bunches and wrinkles which injured the coating on the fabric subsequently wound on the roll. 75

While in most instances the tip drawn canvas apron will constitute a sufficiently smooth foundation covering for the fabrics 80 wound on the roll, yet in some cases where very delicate fabrics are to be wound a cushion surface of greater smoothness may be had by securing a pad to the apron adjacent its tip. This pad may be of any suitable material conveniently formed of two layers of canvas and an intermediate layer of felt stitched together and to the portion of the apron beneath the same. This pad should be of a length corresponding to the 85 circumference of the roll. As stated, each end of the apron is provided with a spreader tip as 49 and each end may also be provided with a pad. Thus the apron is rendered 90 exchangeable end for end. 95

Having described the means for detachably connecting the apron with the take-up roll, I will now describe means for detachably connecting the opposite end of said apron with the fabric wound on the let-off 100 roll 11 referred to at the feeding-in end of the machine. For this purpose there is provided a double hook (Figs. 2 and 7 to 10) comprising a narrow plate 57 preferably curved to conform to the contour of the 105 take-up roll and of a length preferably somewhat greater than the width of the material to be fed and having its edges bent over toward one another to form hooks 57^a, 57^b. One of these hooks may be connected to the 110 apron 47 and the other may be connected to the material to be fed. To assist in securing the fabric to the hook 57^b there may be provided a long, narrow clamp strip 59 of metal or other suitable material. To facilitate its clamping operation and prevent said strip from being separated from said hook 57^b or misplaced, said strip may be provided with fulcrum arms 61 having ends secured to the opposite ends of the strip 59. These 115 arms project substantially perpendicularly from said strip and are adapted to parallel the ends of the hook plate 57. To permit said strip to swing about the end of the hook 57^b as more fully hereinafter described, said side arms may have flanges 63 slotted as at 65 to receive fulcrum pins 67 projecting from the opposite ends of the hooks 57^b. To facilitate the introduction of said pins into said slots, said flanges may be slotted as at 120 125 130

68 (Figs. 8 and 10) to permit said flanges to spring out of their normal plane sufficiently to receive said pins.

The fabric to be treated, before introduction into the machine, is wound on a roll in a winding machine which may be of any suitable construction. Before winding the fabric on this roll, first a tip 49 of an apron 47 such as described is connected to the 10 screws 53 of an empty roll in a manner similar to that described for the take-up roll. The apron is then wound on the roll. A hook plate 57 is then connected to the last wound end of the apron 47 by inserting the 15 metal tip 49 of the latter into the hook end 57^a (Fig. 11). The tip 49 is somewhat greater in width than the depth of the hook end 57^a and therefore projects beyond the entrance to said hook end. As a result the 20 apron wraps around the edge of said tip and extends along the outside of the hook end so that when pulled it tends to maintain said tip securely seated in said hook end. The hook 57 having been connected to the 25 apron 47 as shown in Fig. 11, the hook plate 57 is then connected to an end of the fabric to be wound on the roll. For this purpose the hook plate 57 and an end portion of the apron is folded back so that the hook is inverted and rests on the roll as shown in Fig. 30 12. An end portion of the fabric is then laid on the hook plate and the clamping strip 59 is rocked from its full line position shown in Fig. 12 to its dotted position in 35 said figure, said strip then being in a position on the fabric at the entrance to the throat of the hook 57^b. The clamp strip 59 is then pressed downwardly to the throat of the hook and slid on the fulcrum pins 67 40 into said hook, carrying with it the fabric which follows or wraps about said strip, the latter with the fabric wrapped about it being then inclosed in the hook 57^b. The hook plate 57 is then dropped back to its 45 position shown in Fig. 11 and the roll rotated to bring the hook plate into a position to rest on top of said roll as shown in Fig. 13. The hook plate when dropped back to the position shown in Fig. 11 is again inverted 50 and as a result the fabric will wrap about the outer edge of the clamp strip which should be of a width to project somewhat beyond the end of the hook and when pulled will tend to force or seat the strip into said hook with a force proportional to the pull on the fabric. Preferably the end of the fabric attached to the hook 57^b should be of a length sufficient to wrap about the 55 edge of said hook and lie between the standing portion of the fabric thereat and the outer face of said hook thereby adding to the security of the connection of said hook with said fabric. The roll is then rotated 60 and the fabric to be treated is completely wound thereon. The end of the fabric last 65

wound is then connected to another hook plate 57 similar to the one described for connecting the first wound end of the fabric to the apron on the roll. For this purpose such hook plate is laid upon the roll as 70 shown in Fig. 14, and the last wound end of the fabric is folded back to overlie said hook plate and is connected thereto in a manner similar to that previously described. The hook is then dropped back into the position shown in Fig. 15 and the fabric is 75 completely wound on said roll and may be secured thereto in any suitable manner. Herein this is effected by a securing pin 70 (Fig. 17) comprising wire legs 71 and 73 80 connected by a coil spring 75. The leg 73 may have an indent prong end 73^a.

In use the head 71^a of the leg 71 is inserted in the hook end 57^a (Fig. 18) and the prong leg may be pulled away from the head carrying leg and its prong inserted into the fabric on the roller. The separation of said legs will tension the spring and securely hold the plate 57 to the roll and prevent unwinding of the fabric while the roll 90 is being carried from the winding machine to the fabric coating machine. After the roll reaches the coating machine it is placed on the arms 17 shown at the left of Fig. 1. The fabric is then in readiness to be connected to the end of the apron already in the machine. For this purpose the hook plate is released from the roll and led up to the end of the apron already in the machine at the coating roller and the tip of said apron is inserted in the hook end 57^a of the hook plate 57, as shown in Fig. 16. The fabric is now connected to the machine in readiness to be fed therethrough. The machine is started and the coating knife and apron 47 with the fabric connected thereto is fed into the machine. The coating knife 23 is raised to permit the passage of the hook 57 between the latter and the coating roll 21, whereupon the knife is lowered into engagement 100 with the fabric and the coating substance is laid on the fabric above the roll back of the coating knife 23 as described. The machine continues to operate until the entire length 110 of the fabric has been coated. The coating knife 23 is then raised to permit the hook plate 57 connecting the trailing end of the fabric with the apron first wound on the let-off roll to pass beneath said knife. This apron then follows the trailing end of the 115 fabric through the machine from the coating roll over the guide roll 35 thence to the take-up roll 39. The arrival of the end of the apron at the take-up roll marks the completion of the winding of the fabric on the latter. The end of the apron is then disconnected from the end of the fabric at the take-up roll simply by slipping the apron tip out of the hook end 57^a. The take-up roll 120 is then removed from the machine and an 125 130

empty roll inserted in its stead the end of the apron remaining in the machine at the take-up roll being then hooked over the take-up roll screws 53 as before. By this arrangement the apron following the trailing end of the fabric remains in the machine in readiness to lead in the introductory end of the next fabric to be treated. Thus there is always an apron in the machine and it is merely necessary to connect one end of said apron to the take-up roll and the other end to the fabric to be treated to feed the fabric through the machine. No further attention on the part of the operative is necessary until the fabric is completely wound on the take-up roll.

In some instances instead of always placing a new roll of material at the feeding-in end of the machine, it is desirable to apply one or more additional coatings to the same fabric. In such case the let-off roll filled in the first coating operation is exchanged with the let-off roll emptied by said operation and the fabric is connected to the apron in the machine and passed therethrough to receive another coating as before.

It will be apparent that by my invention the long introductory strip of material previously sewed to the opposite ends of the fabric to be treated is eliminated; it is not necessary that the introductory end of the fabric to be treated, be manually led from the coating roll around the guide roll to the take-up roll, as has been previously necessary, but there is always an apron in the machine in readiness to lead in the fabric; the apron by the hook and tip connection described may be quickly and easily attached and detached from the fabric without the time loss hitherto occasioned in sewing the ends of the fabric to strips; there is no wrinkling at the connection of the apron with the fabric but, on the contrary, the latter is maintained smooth throughout and without any loss of material such as has previously been had by old methods. It is not necessary to wait for the trailing apron to wind up on the take-up roll since the apron is disconnected from the fabric on its arrival at the take-up roll. One apron suffices where two strips previously have been necessary, owing to the fact that the same apron is used for conducting the trailing end of the fabric from the coating roll to the take-up roll and then for conducting the introductory end of the next fabric to be treated.

While I have described my invention for purposes of illustration as applied to a coating machine, it will be understood that it also applies to a variety of other machines.

Claims:

1. In a machine of the class described the combination of take-up means; an apron

for conducting the leading end of a strip of material from the feeding-in end of the machine to said take-up means; an apron for conducting the trailing end of said strip and the leading end of a succeeding strip of material to said take-up means; and means for detachably connecting said aprons to said strips.

2. In a machine of the class described the combination of take-up means; flexible means for conducting the leading end of a strip of material to said take-up means; flexible means for conducting the trailing end of said material to said take-up means; and means for detachably connecting both of said flexible means with said material, whereby the flexible means for conducting the trailing end of one strip may be left in the machine in readiness to conduct the leading end of a succeeding strip.

3. In a machine of the class described the combination of take-up means; and aprons having provision for detachable connection with the opposite ends of a strip of material for conducting the leading and trailing ends of the latter through the machine to said take-up means.

4. In a machine of the class described the combination of let-off means; take-up means; aprons for conducting the leading and trailing ends of a strip of material from one to the other; and means for detachably connecting said aprons with said strip whereby the trailing apron may remain in the machine in readiness to lead a succeeding strip from said let-off to said take-up means.

5. In a machine of the class described the combination of take-up means; an apron for conducting material thereto; a hook for connection with said apron; a clamp strip for detachably securing an end of said material in said hook; and means connecting said strip to said hook having provision permitting movement of said strip to and from clamping position without separation from said hook.

6. In a machine of the class described the combination of take-up means; an apron for conducting material thereto; a hook for connection with said apron; a clamp strip for detachably securing an end of said material in said hook slotted arms on said strip and pins on said hook projecting into said slots.

7. In a machine of the class described the combination of take-up means; a symmetrical apron having spreader terminals exchangeable end for end, said apron being of a length to extend from the feeding-in end of the machine to said take-up means; and means for detachably connecting said terminals to said take-up means and to a strip of material to be treated.

8. In a machine of the class described, the combination of take-up means; a symmet-

rical apron having stiff terminals exchangeable end for end; and means for detachably connecting said terminals to strips of material to be treated.

5 9. In a machine of the class described the combination of take-up means; a symmetrical apron having spreader tips permanently secured thereto, said apron being of a length sufficient to extend from the feeding-in end of the machine to said take-up means; and means for detachably connecting either of said tips to said take-up means or to a strip of material at will.

10 10. In a machine of the class described the combination of take-up means; an apron having stiff spreader terminals, said apron being of a length sufficient to extend from the feeding-in end of the machine to said take-up means; and means to connect said 15 apron with a strip of material and having

provision for connection with either of said terminals merely by the assembly thereof.

11. In a machine of the class described the combination of take-up means; an apron having spreader terminals exchangeable end 25 for end; and means for detachably connecting said terminals to strips of material including a double hook, one hook having a clamp strip for connecting the strip of material thereto, and the other hook being 30 formed for connection with said terminals merely by the insertion of the latter in said hook.

In testimony whereof, I have signed my name to this specification, in the presence 35 of two subscribing witnesses.

CARL J. LANDIN.
